UNITED STATES PATENT OFFICE.

ROBERT A. BROWN, OF CHICAGO, ILLINOIS.

LIFE-BOAT.

SPECIFICATION forming part of Letters Patent No. 748,919, dated January 5, 1904.

Application filed December 24, 1902. Serial No. 196,468. (No model.)

To all whom it may concern:

Be it known that I, ROBERT A. BROWN, a citizen of the United States of America, and a resident of Chicago, in the county of Cook and State of Illinois, have invented certain new and useful Improvements in Life-Boats, of which the following is a specification.

My invention relates to that class of life-boats which is provided with an inner car arranged to remain in equilibrium independently of the rolling or rotating of the outer shell or hull of the boat through the action of the waves or propelling mechanism.

The main objects of my invention are to provide in a boat of this class a suitable arrangement of the various parts, so that same may be readily constructed entirely of steel for the purpose of making the boat fireproof, to provide improved mechanism for propelling a boat of this type, to provide an improved arrangement of parts suitable for properly ventilating the boat, and to provide durable and efficient steering-gear by means of which the boat may be guided either from the exterior or interior of its car. I accomplish these objects by the device shown in the accompanying drawings, in which—

Figure 1 is a longitudinal vertical section of a life-boat constructed according to my invention. Fig. 2 is a transverse vertical section along the line 2 2 of Fig. 1. Fig. 3 is a transverse section on the line 3 3 of Fig. 1.

In the construction shown the hull consists of a shell 4, substantially cylindrical in form and somewhat reduced in diameter at its ends, and is subdivided into five compartments by means of the four transverse bulkheads 5, 6, 7, and 8. The end compartments 9 and 10 are water-tight and serve as air-tanks for supporting the boat in case some of the adjacent compartments become filled with water. The compartments 11 and 12, being the compartments immediately inward of the air-tanks 9 and 10, communicate with the exterior of the boat by means of the tubular passages 13 and 14, which extend axially through said air-tanks. The compartments 11 and 12 also communicate with the exterior of the shell by means of an annular series of air-ports 15. The air-ports 15 are provided with glass lights

and are made water-tight by means of the usual gaskets and dogs.

The central compartment 16 is provided at the middle of its length with a supporting frame 17, extending transversely across same and rigidly secured to the shell. The compartment 16 has journaled therein two cylindrical cars 18 and 19, which are journaled at their adjacent ends on a crank-shaft 20, which is rigidly secured to the frame 17. Suitable cranks 21 connect with the ends of the shaft 20 and are supported at their opposite ends by suitable brackets 22, which are rigidly secured to the upper parts of the cars 18 and 19. The bulkheads 6 and 7 are provided with central apertures 23 and 24, and the ends of the cars 18 and 19 which are adjacent to said bulkheads are provided with corresponding apertures. Each of these apertures is surrounded by an annular series of rollers 25, which are journaled on the cars and ride on suitable annular tracks on the flanges 26 and 27, which are rigidly secured to the corresponding bulkheads. The flange 27 projects inwardly of the car 19, beyond the rollers 25, and carries at its inner end an annular series of sprocket-teeth 28, which connect by means of a link belt 29 with a sprocket 30, which is driven by means of an oil-engine 31. The engine 31 is rigidly mounted in the lower part of the car 19. Further communication between the interior of the cars and the exterior of the hull may be had through the water-tight door 32 and a corresponding water-tight door in the outer shell 4. Communication between the two cars may also be had through the apertures 33 in their adjacent ends. The vessel is provided with suitable locking means (not shown in the drawings) for securing the cars 18 and 19 against rotation with respect to the shell when the shell is at rest.

The shell 4 is stiffened longitudinally by a plurality of inner keelsons 34 and transversely by means of a plurality of spiral flanges 35, extending around the outer surface of said shell. The flanges 35 also serve the purpose of propelling the device through the water when the outer shell 4 is rotated.

The device is steered by means of a rudder 100

36, which is supported by a suitable truss 37. The truss 37 is rigidly connected to the after end of the car 18 and is braced at the after end of the passage 13 by means of a ring 38, fitting within a corresponding ring 39, which is secured to the walls of the passage 13. The joint between the rings 38 and 39 is rendered water-tight by means of a cup-leather packing 40. A platform 41 extends along the top of the truss 37. The aperture within the ring 38 is preferably provided with a water-tight door 42, having a glass light therein. The rudder 36 is so arranged that it may be either operated by a tiller 43 from the platform 41 or by a wheel 44 within the car 18. Air is admitted to the interior of the boat through the passages 13 and 14.

The operation of the device shown is as follows: Passengers enter the boat through the passages 13 and 14 before the same is launched. To propel the device through the water, the outer shell 4 is caused to revolve by means of the engine 31 or if the engine is not in working order by means of the cranks 21. The cars 18 and 19 remain in equilibrium on account of the location of the ballast and passengers contained therein. The cranks 21 also serve as convenient means for starting the engine when an oil-engine is used.

It will be noticed that the spiral flanges 35 serve the double purpose of giving transverse stiffness to the shell-plating and of forming propelling-blades for driving the vessel through the water when the shell is rotated.

The timber-heads 45 are used for securing ropes for the purpose of lowering the vessel or warping it alongside of a ship, wharf, &c., or for anchoring when offshore. Supplies may be carried in the bunkers under the seats in the cars 18 and 19. The truss 37 also carries pipes which lead overboard, such as engine-exhaust, sanitary, and other waste pipes. These pipes are omitted from the drawings for the sake of clearness.

The operation of other features of the device shown will be apparent from the foregoing description.

It will be seen that numerous details of the construction shown may be altered without departing from the spirit of my invention. I therefore do not confine myself to such details, except as herinafter limited in the claims.

What I claim as my invention, and desire
55 to secure by Letters Patent, is—
1. In a boat of the class described, the combination of a horizontally-disposed hull of substantially circular transverse cross-section, comprising a shell of sheet metal, a plurality of longitudinally-disposed stiffening-bars secured to the inner surface of said shell, and a transversely-disposed stiffening-bar extending spirally around the outer surface of said shell, said outer stiffening-bar having an
60 outwardly-projecting flange; a car journaled concentrically within said hull; and means
65 for connecting the car to the hull.

for rotating said hull about said car and propelling same, through the action of said outer flange, substantially as described.

2. In a boat of the class described, the combination of a hull of substantially circular transverse cross-section; an outer propelling-blade on said hull; a car journaled concentrically within said hull upon a horizontally-disposed axis; said hull being revoluble on said axis around said car; said car having a central aperture in one end of same; a transverse bulkhead extending across said hull near the open end of the car and having therein a central opening corresponding to the aperture in said car; an annular flange rigidly secured to said bulkhead around said opening and extending through said aperture into said car; an annular track on said bulkhead; suitable rollers riding upon said track and supporting said car; a motor mounted in said car; and suitable gearing connecting said motor with said flange inwardly of said rollers and adapted to cause said hull to rotate around said car, substantially as described. 90

3. In a boat of the class described, the combination of a hull of substantially circular transverse cross-section; an outer propelling-blade extending spirally around said hull and rigidly secured thereto; a car journaled concentrically within said hull upon a horizontally-disposed axis; said hull being revoluble on said axis around said car and having an opening at each end in line with said axis; said car having rigidly secured thereto a platform extending through one of said openings in suitable manner to leave a free passage through said opening above the platform and provided with a suitable bearing-surface to permit the rotation of said hull around said platform; a rudder supported by said platform, having a tiller above the platform outside of said hull; and a suitable connection extending along the platform to the inside of the car for operating said rudder, substantially as described. 95 100 105 110

4. In a boat of the class described, the combination of a hull of substantially circular transverse cross-section; an outer propelling-blade extending spirally around said hull and rigidly secured thereto; a car journaled concentrically within said hull upon a horizontally-disposed axis; said hull being revoluble on said axis around said car and having an opening at each end in line with said axis; said car having rigidly secured thereto a platform extending through one of said openings in suitable manner to leave a free passage through said opening above the platform and provided with a suitable bearing-surface to permit the rotation of said hull around said platform; a rudder supported by said platform, having a tiller above the platform outside of said hull; and a shaft journaled under said platform, suitably geared to said rudder and extending into the car for operating the rudder, substantially as described. 115 120 125 130

5. In a boat of the class described, the combination of a hull of substantially circular transverse cross-section; an outer propelling-blade extending spirally around said hull and rigidly secured thereto; said hull having a transverse brace across its middle part; and a pair of cars one at each side of said brace and journaled thereto concentric with said hull in a substantially horizontal axis; and a crank rigidly secured to said brace and extending into one of said cars for revolving said hull, substantially as described.
- Signed at Chicago this 20th day of December, 1902.
- ROBERT A. BROWN.
